CHART DEVICE AND TAB HOLDER
THEREFOR

Albert E. Seep, Denver, Colo.

Application April 8, 1944, Serial No. 530,125

10. Claims. (Cl. 40—64)

1

This invention relates to chart devices, and more particularly to tab holders for use as component parts in building up charts. The chart device of this invention is particularly adapted to be utilized in charts indicating personnel of a business or military organization, or for other similar purposes.

In an organization chart, there may be a number of relatively permanent names, titles, positions, or the like to be indicated and there also may be a number of relatively temporary names, titles, or the like, normally subject to change. Such changes may take place regularly as in military units, or from time to time depending upon turnover in the organization or shifting about of personnel to permit experience to be gained, or for other reasons. Thus, it is desirable that a chart device be flexible and permit additions to or deletions from the chart with relative ease.

Among the objects of this invention are to provide a chart device which is flexible and to which indicia can be added or from which deletions can be made with ease; to provide a tab holder which will hold an indicating tab securely; to provide a tab holder which may be made of relatively light material, yet is strengthened in a novel manner; to provide a tab holder which engages the tab in a novel manner; to provide tab holder stock which may be cut to any desired length; to provide a tab holder or a series thereof which may be affixed to a wall, panel, or the like; to provide a plurality of tab holders, the upper of which may bear a relatively permanent indicating tab, and the remainder of which may be affixed to the upper holder and to each other; to provide a series of tab holders which are readily attached and detached; and to provide such tab holders which are relatively easy to produce and simple to use.

Other objects and novel features will become apparent from the description which follows, taken in connection with the accompanying drawings, in which:

Fig. 1 is a front elevation of a chart device constructed in accordance with this invention and mounted on a board adapted to be hung on a wall;

Fig. 2 is a front elevation of a strip constructed in accordance with this invention and adapted to produce a number of holders for receiving a relatively permanent indicating tab;

Fig. 3 is a front elevation of a strip also constructed in accordance with this invention and adapted to produce a number of holders, one or

2

more of which may be suspended from or attached to a tab holder of Fig. 2;

Fig. 4 is a cross section taken along line 4—4 of Fig. 2;

Fig. 5 is a cross section taken along line 5—5 of Fig. 3;

Fig. 6 is a vertical section illustrating the attachment of the holder of Fig. 3 to the holder of Fig. 2 and to a wall or chart board;

Fig. 7 is a cross section illustrating the attachment of a tab holder to a panel or other support;

Fig. 8 is a cross section of an alternative type of tab holder;

Fig. 9 is a front elevation of a holder and tab illustrating the amount of information that may be placed upon a single tab;

Fig. 10 is a fragmentary vertical section corresponding to the assembly shown in Fig. 6 illustrating a modified form of tab utilizing features 20 of this invention.

In the chart illustrated in Fig. 1, the general title of the chart may be printed or otherwise indicated on a board B, adapted to be hung on a wall or placed in any other position suitable for use. A plurality of tab holders 10 are adapted to hold relatively permanent tabs 11, on which are shown the more permanent indicia, such as sections of a country for sales purposes, military units, or the like. One or more tab holders 12 may be attached to each tab holder 10 in depending relation and attached to board B and to each other in a relatively simple manner, so that additions to or deletions from the chart are relatively easy. Tab holders 12 are adapted to hold tabs 13 on which are shown less permanent indicia, such as the names of salesmen or field representatives, or the names of personnel of a military unit, such as in the Service of Supply. The tabs 13 are, in general, replaced more often than tabs 11, the latter of which may be pasted, glued or otherwise attached to the holders.

Tab holders 10 may be constructed from a strip 14 of Figs. 2 and 4, by cutting or severing the strip into desired lengths. Strip 14 is provided with a flange 15 along one edge thereof, and may be made of relatively light material, such as plastic, metal, wood, fibre board, or the like. Flange 15 is adapted to enclose a rod 16, as in Fig. 6, which strengthens the holder. The strip 14 is also provided with a plurality of slots 17 through which any suitable fastening device, such as screws, nails, rivets, or the like may be inserted to fasten the strip to the board or to the background. The tab holder 12 may be made from a strip 20, as in Figs. 3 and 5, provided with an

upper flange 21 and a lower flange 22, and also a hook 23 adapted to extend over and substantially enclose the rod 16 of the tab holder 10. Strip 14 is therefore provided with a plurality of slots 24 through which hooks 23 may be inserted, the hooks extending over the rod 16 to attach the lower tab holder to the upper tab holder as in Fig. 6. As in Fig. 2, the front portion of flange 15 may be provided with additional slots 25 to accommodate the forwardly extending portions of hooks 23.

A border 26 extends downwardly from the forward edge of upper flange 21, and a border 27 extends upwardly from the forward edge of lower flange 22, to accommodate an indicating tab 28 upon which is printed or otherwise shown a name or other indicia. The tab 28 may be placed in either the front or the rear of the tab holder, as shown, the convex lower surface of the upper flange 21 and the convex upper surface of rod 16 being adapted to hold the tab in position against the borders 26 and 27 or against the strip. Or, as illustrated in Fig. 10 a thicker tab 28x may be used having a notch 50 and 51 at each side adapted to engage the convex surfaces, the other parts shown in this view, namely B', 12x, 26x and 27x, corresponding in all essential respects to the similarly numbered parts shown in Fig. 6. The ability to place the tabs at either the front or the rear of the tab holder becomes of advantage when it is known that there will be a change in the chart within a short time, and the new tab can be prepared at the same time as the one to be used until the change is made. Thus, the front tab may be used until the time of the change, at which it may be removed to expose the rear tab to view. The removed tab may be discarded or kept for future use, depending upon the circumstances.

A plurality of indicating tab holders may be attached together by means of the hooks, the hooks passing through slots 29 and extending over and substantially enclosing the rod 16 of the tab holder next above. Since the border 27 extends upwardly, it is unnecessary to provide slots in the border to accommodate hooks, since the hooks will fit into the space between rod 16 and the border.

Strip 20 may also be provided with suitable means for fastening the tab holder to a background board or other support, such as a file cabinet or the like. At predetermined intervals the strip may be provided with key-shaped slot 31 within a countersink 32, so that the tab holder may be attached to the support by a nail or other suitable means, such as a standard split-shank paper fastener 33, as in Fig. 7. The paper fastener 33 extends through slot 31, the head thereof being disposed with countersink 30 to eliminate any obstruction to the insertion or withdrawal of tabs within the holder 12. The tab holder is attached to a support 34, such as the wall of a filing cabinet, the support being provided with a hole 35 through which fastener 31 passes, the legs of the fastener shank being bent over against a washer 36.

An alternative construction of tab holder is illustrated in Fig. 8. As before, a plurality of tab holders may be made by cutting a strip 49 to suitable lengths, the strip being provided with substantially identical upper and lower flanges 41 have a thickened center providing convex inner surfaces in substantially the same manner as flange 21 of Fig. 5, except that the outside periphery of each flange is also convex to provide

a relatively thick central section which imparts strength and rigidity to the tab holder. The upper and lower flanges may be provided with borders 42, for the same purpose as border 26 of Fig. 6, and an indicating tab may be inserted in either the front or the rear of the tab holder, or a notched tab may be used which engages the convex surfaces. The tab holder of Fig. 8 is particularly useful as a name or title plate or the like, or when only one tab holder is to be used, as on a filing cabinet or the like.

The tab holders of Figs. 2, 3 and 8, particularly when made of plastic or similar material, may be provided in any desired color or combination of colors, to lend distinctiveness to the chart and also to segregate each section of the chart. Any desired color scheme or combination may be used, such as different colors for each division, or a different color for the managers or key personnel. The rod 16 may be of metal, wood, or a rolled paper tube impregnated with a plastic or the like and then baked to provide strength with lightness in weight, or the rod 16 may be solid plastic or the like.

25 The strip 14, from which the tab holders 10 are made, the strip 20, from which tab holders 12 are made, the strip from which holders 49 are made, and rods 16, may be any desired length originally, such as 8 in., 12 in., or 24 in., so that a plurality 30 of tab holders of even length, such as 1 in., 2 in., or 3 in., etc., may be made from each strip. Preferably, slots 17 in strip 14, and slots 31 in strip 20 are spaced so that the strip may be severed between two closely adjacent slots to provide a tab holder 1 in. long having a pair of slots adjacent each end, although any other desired increment of length may be provided.

Although in the chart of Fig. 1, only one line of printing has been shown on each tab, it will be understood that the size and shape, and particularly the number of lines of printing on each tab, may be varied as desired. For instance, the tab holder 12 of Fig. 9 permits the insertion of a relatively large tab 13' on which three lines of printing, for instance, may be placed. It will be understood, of course, that the tab holder may be larger or smaller in accordance with the amount of information to be placed thereon, and more particularly the manner in which the information is placed thereon. By utilizing relatively long strips, as explained previously, the length of the tab holder may be varied as desired.

From the foregoing, it will be apparent that the chart device and tab holders therefor, constructed in accordance with this invention, permit a chart of any size or shape to be built up readily, and also permit additions and deletions to be made with ease. A tab holder constructed in accordance with this invention is also particularly advantageous, since it is relatively strong due to either a rod in one flange or thickened sections in both upper and lower flanges, and also may be used as a name plate or for other similar use.

65 It will be understood that various changes may be made, that modifications of this invention other than those described may exist, and that other uses of the tab holders may be found, all without departing from the spirit and scope of this invention.

70 What is claimed is:

1. For a chart device, a tab holder comprising a flat body portion having upper and lower flanges terminating in tab-retaining borders substantially parallel to said flat surface and the inner

surfaces of the intermediate portion of the flanges providing convex surfaces for engagement with the upper and lower edges of an indicating tab.

2. For a chart device, a tab holder having upper and lower tab-retaining flanges, and a rod extending along one edge of said tab holder and substantially enclosed by one of said flanges.

3. For a chart device, a tab holder as defined in claim 2, in which said rod is adapted to engage one edge of the tab inserted in said holder.

4. For a chart device, a tab holder comprising a flat body portion having upper and lower flanges terminating in tab-retaining borders substantially parallel to said flat surface and the inner surface of the intermediate portion of at least one said flange providing a convex surface for engaging an edge of an indicating tab.

5. A chart device comprising an upper tab holder having a lower tab retaining flange adapted to substantially enclose a rod; a rod extending through the flange enclosure and a lower tab holder provided with a plurality of hook-like projections adapted to extend over the top of said rod, said upper holder having a plurality of notches through which said projections extend.

6. A strip for forming a plurality of tab holders, said strip having a lower flange adapted to extend around a reinforcing rod and being provided with slots adjacent to the lower flange and through which may extend hooks attached to the next lower tab holder to engage said rod; and a plurality of longitudinally spaced slots through which a fastener may extend, said slots being so disposed that said strip may be severed between two closely adjacent slots to provide a tab holder having a predetermined length.

7. A strip for forming a plurality of tab holders, said strip having a convex upper flange and a concave lower flange with a border extending downwardly from the outer edge of said upper flange and upwardly from the outer edge of said lower flange, said concave lower flange being adapted to receive a reinforcing rod; a plurality of hooks extending from the upper edge of said strip for attaching a tab holder formed from said strip to the tab holder next above and adapted

to at least partially encircle a reinforcing rod of the tab holder next above; and a plurality of slots adjacent the lower flange of said strip through which hooks of the tab holder next below may extend to engage said reinforcing rod.

5 8. A tab holder comprising a strip having upper and lower flanges provided with a thickened center portion producing convex surfaces; and borders extending upwardly from the edge of said lower flange and downwardly from the edge of said upper flange.

10 9. In a chart device, a plurality of tab holders having upper and lower flanges, the lower flanges of each tab holder being adapted to receive a reinforcing rod and the upper edge of each tab holder being provided with a hook for engaging the rod of the next tab holder above, said upper flange forming a convex surface and said rod also forming a convex surface for holding a tab adjacent the outer edges of said flanges or against said strip; and a reinforcing rod in each tab holder.

15 10. A tab holder comprising a strip having an upper flange provided with a downwardly extended tab retaining border; a lower flange provided with an upwardly extended tab retaining border; and means associated with said flanges and providing a convex surface adjacent the center of each flange whereby an indicating tab may be held adjacent the body of said strip or adjacent the bodies of said flanges.
